UNITED STATES PATENT OFFICE.

WALTER M. DANN, OF WILKINSBURG, PENNSYLVANIA, ASSIGNOR TO WESTINGHOUSE ELECTRIC AND MANUFACTURING COMPANY, A CORPORATION OF PENNSYLVANIA.

TRANSFORMER.

1,279,994.

Specification of Letters Patent. Patented Sept. 24, 1918.

Application filed September 10, 1915. Serial No. 50,101.

To all whom it may concern:

Be it known that I, WALTER M. DANN, a citizen of the United States, and a resident of Wilkinsburg, in the county of Allegheny and State of Pennsylvania, have invented a new and useful Improvement in Transformers, of which the following is a specification.

My invention relates to electrical translating devices, and it has special reference to air-cooled transformers.

More particularly, my invention refers to air-blast transformers of the shell type of construction that are cooled by means of forced drafts traversing ventilating ducts which may be disposed between the coils, between the core-members, and between the core-members and the coils.

Heretofore, the core-members and coils comprising an air-blast transformer have usually been positioned in a casing which inclosed the transformer. Forced drafts of air were circulated in the casing in order to ventilate the transformer structure and, in this instance, air currents were directed between the inner walls of the casing and the adjacent sides of the core-members. This method of construction was expensive and also produced a transformer that was cumbersome to handle.

Since transformers of the shell type of construction usually require two similar core members that are spaced a short distance from each other, it is necessary to provide a ventilating means which is adequate to properly cool the core members. Shell-type transformers embodying the aforementioned method of construction are now commonly used, the inclosing casing, however, being dispensed with. As a substitute for an inclosing casing, a casing is provided at the lower portion of the core members and at the upper portion thereof only, in order to inclose the projecting coil-ends, the terminal boards, etc. The lower end casing constitutes an air chamber into which forced air drafts for ventilating the transformer are admitted, and these air currents, traversing the ventilating ducts between the core members and the coils, are the only cooling means employed. The core members, as a result, are inadequately ventilated because the air currents are not properly directed across their adjacent sides but pass into the outer air at points in close proximity to the lower

end frame whence they originate. Since the upper portions of the transformer core members tend to become hottest, it is desirable for economical operation to adequately cool the upper portions of the core members. 60

An object of my invention is to provide means, in a shell-type transformer, for ventilating the core-members by properly directing cooling air currents thereupon during the operation of the transformer. Other 65 features of novelty in my present invention are set forth in detail in the following description and pointed out with particularity in the appended claims.

Referring to the drawings, Figure 1 is a 70 view, partially in elevation and partially in section, of an air-blast, shell-type transformer embodying a form of my invention; Fig. 2 is a plan view of the transformer shown in Fig. 1 with a portion of the upper 75 casing removed in order to show the interior construction of the transformer; Fig. 3 is a cross-sectional view of a portion of the transformer taken between the spaced core members; Fig. 4 is a view taken at right 80 angles to the view shown in Fig. 3 and embodying a portion of both core members of the transformer, and Fig. 5 is a perspective view partially in section, of a portion of the transformer shown in Fig. 1. 85

In Fig. 1 and Fig. 5, a core structure 1 of the shell-type construction embraces a plurality of coils 2 and a plurality of coils 3 of the transformer, said coils being spaced from one another in order to permit the insertion of insulating barriers 4 and to provide a series of air or ventilating ducts 5 which afford communication between an air chamber 6, provided in a lower end frame 7, and an upper air chamber 8, provided in 90 an upper end frame 9. The transformer is supported upon the end frame 7 having an opening 10 provided therein through which the ventilating air drafts are admitted into the air chamber 6. Tie bolts 11 extending 100 through the core structure firmly hold the laminations comprising the core structure to one another. The upper casing 9 engages the upper surfaces 12 of inverted U-shaped members 13, the latter being secured 105 to the tie bolts 11, substantially as shown in the drawing. Eye bolts 14, engaging the upper face of the casing 9, securely hold the casing upon the upper portion of the transformer core structure. Outlet bushings 15 110

provide means for electrically connecting the coils of the transformer to the supply and feeder circuits. By means of a door 16, the quantity of air admitted to the transformer may be regulated, the position of said door being controlled by an adjustable handle 17.

The core structure 1, as shown in Figs. 3, 4 and 5, comprises two similar core members 18 and 18^a that are spaced from one another in order to provide a passageway 19 therebetween through which communication is afforded between the air chamber 6 and the outer air. Ordinarily, the air drafts emitted from the air chamber 6 through the passageway 19 will flow to the outer air at points adjacent to the lower portion of the core members. As a result, the upper portions of the core members, which have a tendency to become hottest during the operation of the transformer, are precluded from being adequately ventilated and, consequently, the transformer cannot be economically operated. By means of oppositely disposed deflectors 20 that are secured to the upper portion of the lower end frame 7 and placed intermediate the adjacent sides of the core members 18 and 18^a, the air drafts emitted from the air chambers 6, are directed diagonally across the adjacent sides of the core members, as shown by the arrows in Fig. 1, thereby cooling them throughout their entire length. The deflectors 20 prevent the air drafts from passing directly to the outer air at the lower portions of the core members but direct the air drafts upwardly so that substantially the entire area of the adjacent sides of the core members are exposed to them. As a result, the core members 18 and 18^a are adequately cooled, thereby permitting the transformer to be economically operated.

By referring to Fig. 2, it will be noted that the inverted U-shaped members 13 are disposed at opposite sides on the upper face of the core structure. Since the weight of the transformer is transmitted through the inverted U-shaped members 13 to the eye bolts 14, a spreading member 21 extending transversely of the transformer and composed of a channel member, is secured to the upper surfaces of the members 13, in order to firmly hold them from each other when the transformer is being lifted by a crane. This structure protects the casing 9 and also precludes mechanical strains from being imposed upon the coils 3 and 4.

While I have shown and described, in detail, a transformer constructed in accordance with my invention, it will be understood that many modifications may be made without departing from the spirit and scope of the appended claims.

I claim as my invention:

1. A shell-type transformer comprising

core members exposed to the outer air having a substantially unobstructed passageway disposed between their adjacent sides, a casing positioned beneath said core members and providing an air chamber which communicates with the passageway therebetween, and deflectors positioned adjacent to one end only of said passageway for directing air currents through said passageway and uninterruptedly across the adjacent sides of the core members substantially throughout their entire length. 70

2. An electrical translating device comprising spaced core members exposed to the outer air and having a substantially unobstructed passageway disposed between the adjacent sides thereof, an end frame supporting said core members and providing an air chamber which communicates with the passageway between them, and means positioned adjacent to one end only of said passageway whereby substantially the entire area of the adjacent sides of the core members may be exposed to the uninterrupted travel of air currents that issue from said air chamber. 80

3. An electrical translating device comprising spaced core members exposed to the outer air and having a substantially unobstructed passageway disposed between the adjacent sides thereof, coils embraced by said core members, an end frame supporting said core members and coils and providing an air chamber which communicates with said passageway between the core members, and deflectors disposed at the lower portions of the core members in order to direct air blasts emitted from said air chamber upon the upper portions of the core members. 95

4. An electrical translating device comprising spaced core members exposed to the outer air and having a substantially unobstructed passageway disposed between the adjacent sides thereof, coils embraced by said core members, an end frame supporting said core members and coils and providing an air chamber which communicates with the passageway between the core members, and oppositely disposed deflectors at the lower portions of the core members in order to direct air blasts which are emitted from said air chamber diagonally across the adjacent sides of the core members. 100

5. A shell-type transformer comprising spaced core members exposed to the outer air and having a passageway disposed therebetween which communicates directly with the outer air substantially throughout its entire length, spaced flat coils disposed in parallel relation and embraced by the core members, said coils having air ducts therebetween, a casing below the core members providing an air chamber which communicates with the outer air through the passage 115

120

125

130

way between the core members, an upper casing which communicates with said lower casing through said air ducts between the coils, and means for directing air currents 5 from the chamber provided by said lower casing that uninterruptedly traverse substantially the entire area of the adjacent and exposed sides of the core members.

6. A shell-type transformer comprising 10 spaced core members exposed to the outer air, spaced flat coils disposed in parallel relation and embraced by the core members and extending from both ends thereof, inverted U-shaped members secured to oppo-

site sides of the upper ends of the core members, a casing disposed on the upper side of the core members and inclosing the projecting coil ends and engaging the upper surfaces of said U-shaped members, outlet-bushings extending through the said casing, and 20 eye bolts securing the casing to said U-shaped members through which the weight of the transformer may be transmitted.

In testimony whereof, I have hereunto subscribed my name this 31st day of Aug. 25 1915.

WALTER M. DANN.
